JOHN L. COPPING, OF NEW ORLEANS, LOUISIANA.

BURGLAR-PROOF BOLT ATTACHMENT

1,272,627.

Specification of Letters Patent. Patented July 16, 1918.

Application filed April 10, 1918. Serial No. 227,736.

To all whom it may concern:

Be it known that I, JOHN L. COPPING, a citizen of the United States, residing at New Orleans, in the parish of Orleans and State 5 of Louisiana, have invented certain new and useful Improvements in Burglar-Proof Bolt Attachments, of which the following is a specification.

This invention relates to builders' hardware, and more especially to bolts; and the object of the same is to apply to a bolt, particularly to one which is employed on window blinds and the like, an attachment which will prevent it from being retracted by an 15 unauthorized person inserting something between the slats of the blind.

In many cases the blinds are double and meet at the transverse center of the window. In other cases one large blind covers 20 the entire window, or it may be a slatted door which closes the door opening. In any event, the blind or blinds are often locked in closed position by means of a bolt on the inside. If this bolt is already in place 25 my attachment may be employed across its near end. But I prefer to manufacture the bolt and the attachment at one time, and have so described it in the following specification and illustrated it in the drawings, 30 wherein:—

Figure 1 is an elevation of this improved bolt and its attachment,

Fig. 2 is a horizontal section on the line 2—2 thereof,

35 Figs. 3 and 4 are vertical sections on the lines 3—3 and 4—4 of Fig. 1.

While the members shown might be two blinds, let us assume that B is the blind closing into the frame F. A keeper 1 is secured to the inside of the frame. A base plate 2 is secured to the inside of the blind and has loops 3 upon it in which slides the bolt 4, being moved in either direction by an appropriate handle 5. As shown in Figs. 40 1 and 2 when moved to the left its tip enters the keeper 1 and locks the element B within the element F, and when moved to the right the bolt is unlocked.

Across what we will call the inner end 50 of the bolt I mount the attachment forming the subject matter of the present invention. Here the numeral 10 designates a plate which may be separate from the base plate 2 or formed as a part thereof, according to 55 whether this attachment is applied to a bolt already in place or is made as the bolt

is made. At its upper edge this plate is turned inward at right angles in a guard 11 projecting inward for some distance and overlying the inner end of the bolt and the 60 parts yet to be described. Upstruck from the plate are ears 12 through which is mounted a pin 13 carrying a latch 14 which is preferably provided with a thumb piece 15 as shown in Figs. 1 and 4. Coiled on the 65 pin 13 is a spring 16 under some tension, its tendency being to throw the latch inward toward the plate end and hold it there.

When this attachment is applied as shown, the bolt 4 cannot be retracted until 70 the latch is first raised or moved outward from its base plate 10, and this can only be done by inserting the nail or finger behind the thumb piece 15 and pulling it forward against the tension of the spring 16. As 75 soon as the inner end of the bolt 4 passes under the latch, the latter may be released and the bolt slides along behind it. Now when the bolt is again projected to throw its tip into the keeper 1 its rear end slides out 80 from under the latch and the latter snaps against the plate 10 under the tension of the spring 16. The important feature of my invention, however, is the guard plate 11 overlying this latch and in fact overlying 85 and protecting everything at the inner end of the bolt; and therefore an unauthorized person can hardly insert a bent wire or the like through the slats of the blind B and slide the bolt backward, because the bolt 90 is latched in its locked position in a manner which will be obvious. This is on the assumption that this bolt is applied to the lower cross bar of the blinds. Even if we assume that it is applied to the midrail of 95 a slatted door and that someone might reach upward through the slats in a lower panel, the wire could hardly be manipulated so as to be passed under the latch and raise the same, and at the same time another wire introduced and borne against the handle 5 to retract the bolt. Therefore this device 100 practically locks the bolt in closed position against the manipulation of an unauthorized person from the outside.

105 The foregoing description and the drawings have reference to what may be considered the preferred, or approved form of my invention. It is to be understood that I may make such changes in construction 110 and arrangement and combination of parts, materials, dimensions, etcetera, as may prove

expedient and fall within the scope of the appended claims.

Having thus fully described my invention, what I claim as new and desire to secure by Letters Patent, is:—

1. The herein described bolt lock comprising a base plate disposed at the rear end of the bolt and having upstruck ears, its upper edge being bent at right angles into a guard overhanging the bolt and the ears, a pin pivotally mounted through said ears and carrying at one end an upstanding latch provided with a thumb-piece, and a spring coiled on the pin between the ears and throwing said latch normally toward the base plate.

2. In a bolt for slatted doors and the like, the combination with a keeper, the base plate for the door having an enlarged rear end whose upper edge is bent inward at right angles to its bottom, guides on this plate, and a bolt slidably mounted through said guides; of a latch hinged at its lower end to said base plate at a point to pass the rear end of the bolt when the latter is projected, its upper end at this time standing beneath said guard, and a spring bearing said upper end normally against the enlarged portion of the base plate, for the purpose set forth.

3. In a device of the class described, the combination with a keeper adapted to be mounted on one member, a base plate adapted to be mounted on another member, its

upper edge bent inward at right angles into a guard, and a bolt slidably mounted on the base plate with its tip adapted to enter said keeper, of guides upstruck from the lower portion of the base plate, a pin rotatably mounted therein, a latch fast on and upstanding from one end of the pin and having a thumb-piece at its free end, the latch moving in a plane across the rear end of the bolt when the latter is projected, and a spring turning said pin normally in a direction to press the free end of the latch against the base plate, for the purpose set forth.

4. In a device of the class described, the combination with a keeper adapted to be mounted on one member, and a horizontally sliding bolt adapted to be mounted on another member; of a base plate attached to said last-named member at the rear end of the bolt, a latch pivoted at its lower end to said plate on a line parallel with the length of said bolt, yielding means pressing it normally against said plate in rear of the bolt when the latter is projected, and a fixed guard on the base plate overlying the latch. In testimony whereof I affix my signature in presence of two witnesses.

JOHN L. COPPING.
